UNITED STATES PATENT OFFICE

WILLIAM M. BLECKER, OF CANTON, OHIO, ASSIGNOR OF FIFTY-ONE PER CENT TO
EDWARD A. LANGENBACH, OF CANTON, OHIO

CONTINUOUS SHEET MILL

Application filed June 23, 1928. Serial No. 287,745.

The invention relates to the continuous rolling of sheet bars, slabs or light plates into sheets of desired gauge, and the object of the improvement is to provide an apparatus in which the slabs or the like may be sheared from a continuous strip, matched or piled into packs and passed through a series of mills, cooled, pickled, cold rolled, annealed and further cold rolled, all in a single continuous operation.

A further object is to provide means for opening the pack and separating the sheets before they enter the pickling tank, all of the apparatus from this point on being arranged in tandem whereby the sheets separated from the pack may be carried in spaced pairs through the apparatus.

A further object is to provide means for withdrawing the separated sheets at this point and passing them in tandem through one or more stands of cold rolls and a double continuous annealing furnace in order to produce one pass cold rolled and annealed sheets.

By passing the sheets entirely through the mechanism above described, full finished automobile stock can be produced or the sheets may be removed before passing through the final cold rolls if pickled and annealed sheets are desired.

An embodiment of the invention is illustrated in the accompanying drawings, in which

Figures 1, 1a and 1b are a complete plan sectional view of the rolling apparatus; and

Figs. 2, 2a and 2b are a complete vertical sectional view thereof.

Similar numerals refer to similar parts throughout the drawings.

The apparatus is arranged to be located in continuity with a strip mill or the like adapted to furnish strips of suitable gauge for cutting into slabs or sheet bars.

The strip may be delivered to the shear 1 where it is cut into slabs or the like and deposited upon the matching table 2. The slabs are piled or matched into packs of two or more upon this matching table and may then be delivered upon a turning table 3 and rotated a quarter turn before passing into the

heating furnace 4, in order to provide for cross rolling if desired.

The packs of slabs are carried on the conveyer 5 through the heating chamber and as they emerge therefrom the scale may be loosened and removed from the slabs as by the hydraulic nozzle 6 and steam jets 7.

The several slabs or plates in the pack may then be straightened as by the pack straightening device shown generally at 8, after which the pack is carried through a series of four high hot mills shown at 9, the distance between the stands of rolls being increased successively in order to compensate for the elongation of the pack as it passes through the several mills.

The conveyer 5 is arranged to carry the pack through the several stands of hot mills 9 and then through a cooler 10 which may be provided with inlet and outlet pipes 11 and 12 whereby cooling air or inert gas may be circulated through the cooler and over the heated pack to quickly reduce the temperature of the same.

As the cooled pack emerges from the cooler 10 it may be carried through a pack leveler indicated at 13 and then delivered by the roller conveyer 5 onto a chain conveyer 14 which carries the pack through the edge trimming shears 15.

A shear 16 may be provided beyond the chain conveyer 14 for shearing the forward end of the pack before the same is passed through the pack opener 17. The sheets of the pack are loosened from each other as they pass through this pack opener and are delivered onto the roller conveyer 18.

At this point means may be provided for separating the sheets of the pack so that they may be passed through the remaining mechanism singly as sheets. This mechanism is illustrated conventionally as comprising a fluid operated cylinder 19, the plunger 20 of which may be provided with any suitable means, such as the magnet 21 for gripping the top sheet of the opened pack and moving the same laterally away from the pack.

Means, such as a magnet (not shown) may be provided for holding the lower sheet or sheets of the pack against movement while

the top sheet is moved by the plunger 20. The apparatus is arranged in tandem from this point through to the discharge end in order that single sheets, separated from the pack, may be simultaneously carried in pairs through the remaining mechanism.

If it is desired to produce only one pass cold rolled and annealed sheets, a transfer table 22 may be provided just beyond this separating mechanism in order to carry the separated sheets laterally and place them upon the tandem conveyers 23 by means of which the single sheets are passed in spaced pairs through the tandem cold rolls 24 and double continuous annealing furnace 25. One or more stands of the cold rolls 24 may be provided if desired.

Beyond the double continuous annealing furnace may be located hydraulic nozzles 26 and steam jets 27 for loosening and removing scale and the like from the annealed sheets. The sheets may then be delivered to any suitable receiving mechanism located beyond these nozzles and jets.

If it is desired to produce pickled and annealed sheets or full finished automobile stock, the sheets separated by the separating mechanism above described may then be passed in tandem, upon the parallel conveyers 28, through a double continuous pickling tank 29, washing tank 30, drying furnace 31 and cooler 32. This cooler may be of the same construction as illustrated and described at 10, being provided with the inlet and outlet pipes 33 and 34 for circulating a cooling agent such as inert gas or air over the pickled and annealed sheets.

One or more tandem stands of cold rolls 35 may be located beyond the cooler, after which the sheets pass in spaced pairs through the double continuous annealing furnace 36. Hydraulic nozzles 37 and steam jets 38 may be located beyond the annealing furnace to loosen and remove scale and the like from the annealed sheets.

A transfer table 39 may be provided at this point for removing the sheets if pickled and annealed sheets are desired, which need not be cold rolled; and also for cold rolled sheets intended to be galvanized or otherwise coated. If full finished automobile stock is required, the sheets are passed through one or more stands of tandem cold rolls 40 and then in tandem through the leveling rolls 41, being discharged from the end of the mechanism by the tandem conveyers 42.

From the above it will be seen that the light plates or the like may be continuously passed through the apparatus to produce either cold rolled and annealed sheets, pickled and annealed sheets or full finished automobile stock as desired.

By separating the sheets from the pack and carrying the same through the tandem mechanism in spaced pairs, it will be seen

that the hot rolls and associated mechanism which rolls the packs need not be slowed down in order to compensate for the operations upon the single sheets after the pack is opened and separated, thus permitting the entire mechanism to be operated at full speed.

It is not intended to limit the scope of the invention and the claims therefor to the use of four high hot mills and four high cold rolls shown in the drawings and described in the specification, to the exclusion of two high or three high mills; the four high mills being presented herein to illustrate kinds of mills which may be used for carrying out the invention.

I claim:

1. Apparatus for the continuous rolling of sheets from light plates and the like including a heating furnace, a series of hot mills, means for passing the material through the furnace and mills in packs, pack opening and separating mechanism, a double continuous pickling tank, tandem cold rolls, a double continuous annealing furnace, and means for passing sheets in spaced pairs through the pickling tank, cold rolls and annealing furnace.

2. Apparatus for the continuous rolling of sheets from light plates and the like including a matching table, a heating furnace a series of hot mills, means for passing the material through the furnace and mills in packs, pack opening and separating mechanism, a double continuous pickling tank, tandem cold rolls, a double continuous annealing furnace, and means for passing sheets in spaced pairs through the pickling tank, cold rolls and annealing furnace.

3. Apparatus for the continuous rolling of sheets from light plates and the like including a turning table, a heating furnace, a series of hot mills, means for passing the material through the furnace and mills in packs, pack opening and separating mechanism, a double continuous pickling tank, tandem cold rolls, a double continuous annealing furnace, and means for passing sheets in spaced pairs through the pickling tank, cold rolls and annealing furnace.

4. Apparatus for the continuous rolling of sheets from light plates and the like including a matching table, a turning table, a heating furnace, a series of hot mills, means for passing the material through the furnace and mills in packs, pack opening and separating mechanism, double continuous pickling tank, tandem cold rolls, a double continuous annealing furnace, and means for passing sheets in spaced pairs through the pickling tank, cold rolls and annealing furnace.

5. Apparatus for the continuous rolling of sheets from light plates and the like including a shear, a heating furnace, a series of hot mills, means for passing the material

through the furnace and mills in packs, pack opening and separating mechanism, a double continuous pickling tank, tandem cold rolls, a double continuous annealing furnace, and means for passing sheets in spaced pairs through the pickling tank, cold rolls and annealing furnace.

6. Apparatus for the continuous rolling of sheets from light plates and the like including a shear, a matching table, a heating furnace, a series of hot mills, means for passing the material through the furnace and mills in packs, pack opening and separating mechanism, a double continuous pickling tank, tandem cold rolls, a double continuous annealing furnace, and means for passing sheets in spaced pairs through the pickling tank, cold rolls and annealing furnace.

7. Apparatus for the continuous rolling of sheets from light plates and the like including a heating furnace, a series of hot mills, a cooler, means for passing material through said furnace, mills and cooler in packs, pack opening and separating mechanism, a double continuous pickling tank, tandem cold rolls, a double continuous annealing furnace, and means for passing sheets in spaced pairs through the pickling tank, cold rolls and annealing furnace.

8. Apparatus for the continuous and simultaneous, selective rolling of one pass cold rolled and annealed sheets and pickled cold rolled and annealed sheets from light plates and the like including a heating furnace, a series of hot mills, means for passing the material through the furnace and mills in packs, pack opening and separating mechanism, a double continuous pickling tank, tandem cold rolls, a double continuous annealing furnace, second tandem cold rolls, conveying means for passing sheets in spaced pairs continuously through the pickling tank, cold rolls, annealing furnace and second cold rolls, and means for selectively removing and collecting sheets from the conveying means before passing through the second cold rolls.

9. Apparatus for the continuous and simultaneous, selective rolling of one pass cold rolled and annealed sheets and pickled cold rolled and annealed sheets from light plates and the like including a heating furnace, a series of hot mills, means for passing the material through the furnace and mills in packs, pack opening and separating mechanism, a double continuous pickling tank, tandem cold rolls, a double continuous annealing furnace, second tandem cold rolls, leveling rolls, conveying means for passing sheets in spaced pairs continuously through the pickling tank, cold rolls, annealing furnace, second cold rolls, and leveling rolls, and means for selectively removing and collecting sheets from the conveying means before passing through the second cold rolls.

10. Apparatus for the continuous rolling of sheets from light plates and the like including a heating furnace, a series of hot mills, means for passing the material through the furnace and mills in packs, pack opening 70 and separating mechanism, a double continuous pickling tank, tandem cold rolls, a double continuous annealing furnace, means for passing sheets in spaced pairs through the pickling tank, cold rolls and annealing furnace, and means for impinging fluid upon the material after it passes through the annealing furnace.

11. Apparatus for the continuous rolling of sheets from light plates and the like including a heating furnace, a series of hot mills, means for passing the material through the furnace and mills in packs, pack opening 80 and separating mechanism, a double continuous pickling tank, tandem cold rolls, a double continuous annealing furnace, means for passing sheets in spaced pairs through the pickling tank, cold rolls and annealing furnace, and means for impinging fluid upon the material after it passes through each furnace.

12. Apparatus for the continuous and simultaneous, selective rolling of one pass cold rolled and annealed sheets and pickled cold rolled and annealed sheets from light plates 95 and the like including a matching table, a heating furnace, a series of hot mills, means for passing the material through the furnace and mills in packs, pack opening and separating mechanism, a double continuous 100 pickling tank, tandem cold rolls, a double continuous annealing furnace, second tandem cold rolls, conveying means for passing sheets in spaced pairs continuously through the pickling tank, cold rolls, annealing furnace and second cold rolls, and means for selectively removing and collecting sheets from the conveying means before passing through the second cold rolls.

13. Apparatus for the continuous and simultaneous, selective rolling of one pass cold rolled and annealed sheets and pickled cold rolled and annealed sheets from light plates and the like including a turning table, a heating furnace, a series of hot mills, means for passing the material through the furnace and mills in packs, pack opening and separating mechanism, a double continuous pickling tank, tandem cold rolls, a double continuous annealing furnace, second tandem cold rolls, 115 conveying means for passing sheets in spaced pairs continuously through the pickling tank, cold rolls, annealing furnace and second cold rolls, and means for selectively removing and collecting sheets from the conveying means before passing through the second cold rolls.

14. Apparatus for the continuous and simultaneous, selective rolling of one pass cold rolled and annealed sheets and pickled cold 120

rolled and annealed sheets from light plates and the like including a matching table, a turning table, a heating furnace, a series of hot mills, means for passing the material through the furnace and mills in packs, pack opening and separating mechanism, a double continuous pickling tank, tandem cold rolls, a double continuous annealing furnace, second tandem cold rolls, conveying means for passing sheets in spaced pairs continuously through the pickling tank, cold rolls, annealing furnace and second cold rolls, and means for selectively removing and collecting sheets from the conveying means before passing through the second cold rolls.

15. Apparatus for the continuous and simultaneous, selective rolling of one pass cold rolled and annealed sheets and pickled cold rolled and annealed sheets from light plates and the like including a shear, a heating furnace, a series of hot mills, means for passing the material through the furnace and mills in packs, pack opening and separating mechanism, a double continuous pickling tank, tandem cold rolls, a double continuous annealing furnace, second tandem cold rolls, conveying means for passing sheets in spaced pairs continuously through the pickling tank, cold rolls, annealing furnace and second cold rolls, and means for selectively removing and collecting sheets from the conveying means before passing through the second cold rolls.

16. Apparatus for the continuous rolling of sheets from light plates and the like including a heating furnace, a series of hot mills, a cooler, means for passing the material through the furnace, mills and cooler in packs, pack opening and separating mechanism, a double pickling tank, a double washing tank, a double drying furnace, a double cooler, tandem cold rolls, a double annealing furnace and means for passing sheets in spaced pairs through the pickling tank, washing tank, drying furnace, double cooler, cold rolls and annealing furnace.

17. Apparatus for the continuous rolling of sheets from light plates and the like including a heating furnace, a series of hot mills, a cooler, means for passing the material through the furnace, mills, and cooler in packs, pack opening and separating mechanism, a transfer table, tandem cold rolls and a double annealing furnace communicating with the transfer table, a double pickling tank, a double washing tank, a double drying furnace, a double cooler, tandem cold rolls, a double annealing furnace, and means for passing sheets in spaced pairs through the pickling tank, washing tank, drying furnace, double cooler, cold rolls and annealing furnace.

18. Apparatus for the continuous and simultaneous, selective rolling of one pass cold rolled and annealed sheets and pickled cold rolled and annealed sheets from light plates

and the like including a heating furnace, a series of hot mills, a cooler, means for passing the material through the furnace, mills and cooler in packs, pack opening and separating mechanism, a double pickling tank, a double washing tank, a double drying furnace, a double cooler, tandem cold rolls, a double annealing furnace, a second tandem cold rolls, leveling rolls, conveying means for passing sheets in spaced pairs continuously through the pickling tank, washing tank, drying furnace, double cooler, cold rolls, annealing furnace, second cold rolls and leveling rolls, and means for selectively removing and collecting sheets from the conveying means before passing through the second cold rolls.

19. Apparatus for the continuous rolling of sheets from light plates and the like including a heating furnace, a series of hot mills, a cooler, a pack leveler, means for passing the material through the furnace, mills, cooler and pack leveler in packs, pack opening and separating mechanism, a double pickling tank, a double washing tank, a double drying furnace, a double cooler, tandem cold rolls, a double annealing furnace and means for passing sheets in spaced pairs through the pickling tank, washing tank, drying furnace, double cooler, cold rolls and annealing furnace.

20. Apparatus for the continuous and simultaneous selective rolling of one pass cold rolled and annealed sheets and pickled cold rolled and annealed sheets from light plates and the like including a heating furnace, a series of hot mills, means for passing material through the furnace and mills in packs, pack opening and separating mechanism, a double continuous pickling tank, tandem cold rolls, a double continuous annealing furnace, auxiliary tandem cold rolls and an auxiliary double continuous annealing furnace, conveying means for passing sheets in spaced pairs continuously through the pickling tank, cold rolls and annealing furnace, auxiliary conveying means for passing sheets through the auxiliary rolls and auxiliary annealing furnace, and means for selectively transferring sheets from the first said conveying means to the auxiliary conveying means before passing into the pickling tank.

21. Apparatus for the continuous and simultaneous selective rolling of one pass cold rolled and annealed sheets and full finished cold rolled sheets from light plates and the like including a heating furnace, a series of hot mills, means for passing material through the furnace and mills in packs, pack opening and separating mechanism, a double continuous pickling tank, tandem cold rolls, a double continuous annealing furnace, a second tandem cold rolls, auxiliary tandem cold rolls and an auxiliary double continuous annealing furnace, conveying means for passing sheets in spaced pairs continuously

through the pickling tank, cold rolls, annealing furnace, and second cold rolls, auxiliary conveying means for passing sheets through the auxiliary rolls and auxiliary annealing 5 furnace, and means for selectively transferring sheets from the first said conveying means to the auxiliary conveying means before passing into the pickling tank.

22. Apparatus for the continuous and simultaneous selective rolling of one pass cold rolled and annealed sheets, pickled cold rolled and annealed sheets and full finished cold rolled sheets from light plates and the like including a heating furnace, a series of hot 10 mills, means for passing material through the furnace and mills in packs, pack opening and separating mechanism, a double continuous pickling tank, tandem cold rolls, a double continuous annealing furnace, a second tandem cold rolls, levelling rolls, auxiliary tandem cold rolls and an auxiliary double continuous annealing furnace, conveying means for passing sheets in spaced pairs continuously through the pickling tank, cold rolls, 15 annealing furnace, second cold rolls, and levelling rolls, auxiliary conveying means for passing sheets through the auxiliary rolls and auxiliary annealing furnace, means for selectively transferring sheets from the first 20 said conveying means to the auxiliary conveying means before passing into the pickling tank, and means for selectively removing and collecting the sheets from the first said conveying means before passing through 25 the second cold rolls.

In testimony that I claim the above, I have hereunto subscribed my name.

WILLIAM M. BLECKER.
